UNITED STATES PATENT OFFICE

WILLIAM H. BANFIL, OF BOSTON, MASSACHUSETTS

FOAM-TYPE FIRE EXTINGUISHER

Application filed July 21, 1926. Serial No. 123,956.

This invention relates to fire extinguisherstainer is not immediate but only after an ex-
of the foam producing type and particularly
relates to the portable or hand type of foam
producing fire extinguisher.

A foam producing fire extinguisher of the
5 hand type comprises a casing adapted to con-
tain a gas generating and foam producing
liquid as a water solution of sodium bicarbon-
ate and licorice, and an inner receptacle or
tube adapted to contain an acid or reagent,
10 as aluminum sulphate, which, when caused
to mix with the foam-producing liquid,
generates a foam and a gas which expels the
foam through the hose of the casing. By
15 reason of the characteristics of the foam pro-
ducing materials, the amount of acid solution
preferably should approximate the amount
of foam producing solution; consequently the
acid container or tube has substantial inter-
20 nal diameter and is approximately coexten-
sive with the height of the casing. The open
top of the said container is normally disposed
above the liquid levels and is normally closed
25 by a gravity operated cap or closure which is
adapted to fall away from the opening when
the extinguisher is inverted thereby to permit
the two liquids to commingle and generate
30 foam and a gas pressure.

The acid container or tube is usually com-
30 posed of brass and is tinned inside and out-
side and then given a coating of lead either by
dipping the tinned container in a bath of
molten lead or by applying molten lead to
35 the tinned surfaces. Under these conditions
the container is uniformly coated with a thin
coating of lead; and the intended purpose of
the lead coating is to protect the brass tube
against the action of the acid.

The fire extinguisher is adapted to be main-
40 tained charged, in readiness for instant use
and, when discharged, usually is immediately
recharged, so that the acid container is con-
tinually filled with a charge of acid. It is
45 found in practice that the acid container is
not entirely acid-resistant but is slowly eaten
away in spots, not only at the liquid level, but
also below the level, and finally allows the
liquids to commingle and discharge foam,
50 thereby resulting in a possible damage to sur-
rounding objects. The failure of the con-

55 extended period of time. Some containers fail
in a few months and others in one or two
years. Such a container cannot be con-
sidered to be entirely satisfactory as the ulti-
mate and unintentional discharge of the ex-
tinguisher is always present and the con-
tainers must be replaced from time to time
at an expense to the user.

60 Consequently it is an object of this invention
to provide an acid container for a foam-
producing type of fire extinguisher char-
acterized by being immune or inert to the acid
it is adapted to contain, so that it will be acid-
65 tight for an indefinite period of time.

66 In carrying out this object of the invention
in practice, I provide an acid container com-
posed of an acid-immune or inert vitreous
material, preferably glass, which has ap-
70 proximately the height of the extinguisher-
casing and is of large internal diameter to
contain the requisite supply of acid.

75 It is a further object of the invention to
provide a protective holder for the acid con-
tainer and, to this end the glass container is
removably received snugly within a stiff
metal fluid tight tube or shell and rests upon
80 the bottom thereof and has its side walls sup-
ported substantially throughout by the side
wall of the tube. The protective tube may
be composed of brass and may be lead coated.

85 A further object is to provide means to
hold the glass container removably in place
within the protective holder.

90 It is a further object of the invention to
provide a gravity-operated closure for the
glass acid container, which closure also is
composed of an acid-inert material and, to
this end, I form the closure of a vitreous
95 material as glazed porcelain.

95 A further object is the provision for the
seating of the closure directly upon the glass
container and for a secondary seat of the
closure upon the holder for the container, so
that the holder can serve temporarily as the
acid container and be closed by the closure,
100 in the remote event of the breaking of the
glass container.

105 A yet further object of the invention is
the permanent enclosure of the closure in a

valve cage so that it cannot become lost when the extinguisher is taken apart for cleaning and recharging.

An additional object is the connection of the acid container with the cover for the casing of the extinguisher so that the acid container and its associated elements can be removed directly from the casing by the raising of the cover of the casing.

A further object is generally to improve the construction of fire extinguishers.

Fig. 1 is a sectional elevation through a fire extinguisher embodying the invention.

Fig. 2 is a side elevation in detail of the valve cage.

Fig. 3 is a section along line 3—3 of Fig. 1.

Fig. 4 is a sectional detail of the acid container and associated elements, in the inverted position thereof, and illustrating particularly the position assumed by the closure.

As here shown, the fire extinguisher embodying the invention includes a casing 10 which is adapted to contain the foam and gas producing materials, as a water solution of sodium bicarbonate and licorice. The casing is closed at the bottom and is provided at the top with an open and externally screw-threaded neck 12 which is removably closed by a cover 14 that is screw-threaded on said neck and is provided with a hand wheel 16 by which the cover can be rotated on the neck. A gasket 18 is interposed between the neck and the cover to provide a fluid-tight joint thereat.

A valve cage for the closure of the acid container is carried by the cover and comprises a metal tube 20 having a diameter approximating that of the neck-opening and permanently affixed as by solder or brazing material to the under side of the cover and depending therebeneath within the neck-opening. A collar 22 is secured permanently to the lower end of said tube and is provided with a radially inwardly-directed annular flange 24 which extends into the interior of the tube and cooperates with the cover to provide permanent closures or barriers at the ends of the tube to retain movably therein the closure for the acid container. The side wall of the tube is provided with a plurality of openings or ports 26 of substantial dimensions separated by ribs 28 which serve as guide members for the closure during its movements.

The closure for the acid container comprises a relatively discoidal member 30 composed of an acid-inert material, preferably glazed porcelain and adapted to fit loosely within the valve cage and, when the cage is inverted, to fall from the position illustrated in Fig. 1 to that illustrated in Fig. 4. The closure is provided with an upstanding annular flange 32 that is adapted to engage with the side of the cage and prevent the cramping or jamming of the closure in the

70 cage. The top portion of the valve cage is adapted to provide a compartment in which the closure is adapted to rest, in the inverted position of the extinguisher, in which position the closure is mainly below the ports, so that the ports are freely open, although there is a sufficient extent of the closure accessible at the ports to enable the closure to be manipulated by hand if it should stick in the open position before the extinguisher has been cleaned after being operated. The bottom face 34 of the closure is plane while the marginal portion 36 thereof is inclined downwardly to provide a seat upon the acid container.

75 The holder for the acid container comprises a metal tube 38 which is closed at the bottom and is open at the top and is axially disposed within and extends approximately coextensive with the length of the casing 10. The holder preferably is composed of brass and has a coating of lead upon its surface. The upper end of said holder, about the top thereof, is provided with an externally screw-threaded ring 40 which is permanently 80 affixed to the holder. Said ring is adapted to be screw-threaded removably into the internally screw-threaded lower end 42 of the collar 22 and against the flange 24 thereof, thereby to secure the holder removably connected with the valve cage and thereby to 85 cover 14.

90 The acid container comprises an elongated tube 44 which is composed of an acid-immune and vitreous material, preferably 95 glass. The glass tube is of substantial thickness, for mechanical strength and is received snugly and removably within the holder 38 and rests upon the bottom and is supported over practically its entire height 100 by the side wall of the holder. The glass tube is closed at the bottom and is open at the top. The open top is somewhat drawn in or is provided with a neck 46 which is received 105 within the valve cage and is terminated above the flange 24 in a flat seat 48 against which the inclined valve face 36 of the closure is adapted to rest, in the normal position 110 of the extinguisher, thereby to seal the tube. In this position the lower edge of the closure is spaced above the flange 24 and, in the remote possibility of the glass tube becoming 115 broken, the closure can seat on the flange, thus maintaining the seal on the acid.

120 The glass tube normally is retained in position within its holder by said flange 24 which is adapted for engagement with the neck 46 of the tube. When, however, the holder is unscrewed from the valve cage, the glass tube can be removed readily from the holder.

125 Since the acid container and its associated elements are connected with and carried by the cover 14, they can be removed readily from the extinguisher casing when the ex-

tinguisher is opened for cleaning and recharging, or for inspection, thereby facilitating the operation.

By the provision of the acid-inert construction of the acid container, there is no possibility of its eventually becoming corroded or eaten through and the extinguisher is thereby free from accidental discharge and from container replacements.

The construction may be otherwise modified without departing from the spirit of the invention.

I claim:

1. In a foam-type fire extinguisher of the type having an outer casing adapted to contain the foam-producing liquid, a holder comprising a long open-top, closed bottom fluid-retaining metal tube adapted to be disposed within said casing and to extend approximately co-extensive with the length thereof, and an acid-containing glass tube removably received snugly within said tubular holder and having an upper open end terminated shortly above the open top of said tube, a gravity-operated closure for said glass tube arranged to seat directly on the open top thereof, and means to retain said holder in the aforesaid relation.

2. In a foam-type fire extinguisher of the type having an outer casing adapted to contain the foam-producing liquid, a holder comprising a long open-top closed-bottom fluid retaining metal tube adapted to be disposed within said casing and to extend approximately co-extensive with the length thereof, and an acid-containing glass tube removably received snugly within said tubular holder and having an upper open end terminated shortly above the top of said tube, a collar having a removable connection with the top of said holder and having an inwardly directed flange which overlies said glass tube, below the open top thereof and serves to retain said tube within said holder, a ported valve-cage having a connection at its lower end with said collar above said flange, and a gravity-operated closure for said glass tube slidable in said cage and arranged to seat directly on the open top of said glass tube.

3. In a foam-type fire extinguisher of the type having an outer casing adapted to contain the foam-producing liquid, a holder comprising a long open-top fluid retaining metal tube adapted to be disposed within said casing and to extend approximately co-extensive with the length thereof, a ported valve cage disposed above and having a removable screw-threaded connection with and surrounding the open top of said holder, said cage having an inwardly directed flange, a glass acid-containing tube removably contained snugly within said holder and having its upper open end disposed within and extended above said flange, and

a gravity-operated closure for the open tops of both said glass and metal tubes movably disposed in said cage above said flange.

4. In a foam-type fire extinguisher, an open top casing adapted to contain a foam-producing liquid, a removable cover for said casing, a tube having ports in its side wall connected permanently with said cover and depending therebelow into said casing, a collar permanently attached to the lower end of said ported tube having an inwardly directed flange and an internally-screw-threaded section immediately beneath said flange, an open-top fluid retaining metal tubular holder disposed beneath said ported tube and having its upper end screw-threaded removably in the screw-threaded section of said collar and seated against said flange, an acid container received removably within said fluid retaining holder and having a reduced open top extended above said flange, and a gravity-operated closure for said acid container movably disposed in said ported tube and overlying said flange.

5. In a foam-type fire-extinguisher, a fragile acid container having an open top, a metal liquid-retaining holder enclosing said container having an open top disposed beneath the top of said fragile container, and a closure for said container extended peripherally therebeyond and above and in position also to engage the top of and close said metal holder if said fragile container should break.

6. In a fire extinguisher of the foam-producing type, the combination of a long and narrow cylindrical fluid retaining metal tube which is open at the top and has external screw threads at the top, a cylindrical metal valve cage having ports in its cylindrical wall and open at the bottom aligned with said tube and having a ring surrounding its open bottom provided with internal screw threads in which the external screw threads of said tube are received, said ring having an internal ledge which overlies the top of said tube and extends inwardly over the open top thereof and constitutes a seat against which said tube is screwed, a cylindrical fluid retaining glass tube open at the top snugly received removably within said metal tube and supported at the bottom and sides thereby, said glass tube having its side wall at the top flared inwardly and located within said internal ledge and abutting thereagainst, said ledge thus constituting means to hold said glass tube in place within said metal tube when both are inverted, the top face of said glass tube being horizontal and constituting a valve seat, and a gravity-operated valve contained loosely and slidably within said valve cage having a bottom face which is seated normally upon the valve seat of said glass tube, said valve also overlying and normally spaced above and out of engagement with said ledge.

115
120
125
130

7. In a fire extinguisher of the foam-producing type, the combination of a long and narrow cylindrical fluid retaining metal tube which is open at the top and has external screw threads at the top, a cylindrical metal valve cage having ports in its cylindrical wall and open at the bottom aligned with said tube and having a ring surrounding its open bottom provided with internal screw threads in which the external screw threads of said tube are received, said ring having an internal ledge which overlies the top of said tube and extends inwardly over the open top thereof and constitutes a seat against which said tube is screwed, a cylindrical fluid retaining glass tube open at the top snugly received removably within said metal tube and supported at the bottom and sides thereby, said glass tube having its side wall at the top flared inwardly and located within said internal ledge and abutting thereagainst, said ledge thus constituting means to hold said glass tube in place within said metal tube when both are inverted, the top face of said glass tube being horizontal and constituting a valve seat, and a gravity-operated valve contained loosely and slidably within said valve cage having a bottom face which is seated normally upon the valve seat of said glass tube, said valve having a depending annular rim which protrudes below said seat into the space between the top of said glass tube and said cage and over and normally free from contact with said ledge, said rim and ledge adapted to engage and to constitute a supplementary valve to seal said metal tube in the event of breakage of said glass tube.

8. In a foam-type fire extinguisher of the type having an outer casing adapted to contain the foam-producing liquid, a long acid container adapted to be disposed within said casing and to extend approximately co-extensive with the length thereof and consisting of an inner open-top fluid-retaining shell adapted to contain the acid and characterized by being inert with respect to the acid, and an outer fluid-retaining, open-top and closed-bottom metal tube enclosing said shell and engaging it along its length and providing mechanical support therefor, said shell having an internal acid-resistant coating whereby said shell can also serve as an acid container in the event of breakage of said inner container.

In testimony whereof, I have signed my name to this specification.

WILLIAM H. BANFIL.
